UNITED STATES PATENT OFFICE.

OTTO THIEME, OF ST. LOUIS, MISSOURI, ASSIGNOR TO MOON HOPKINS BILLING MACHINE COMPANY, OF ST. LOUIS, MISSOURI, A CORPORATION OF MISSOURI.

PAPER-SUPPORT FOR WRITING-MACHINES.

1,206,271.

Specification of Letters Patent. Patented Nov. 28, 1916.

Application filed December 3, 1913. Serial No. 804,384.

To all whom it may concern:

Be it known that I, OTTO THIEME, a citizen of the United States, residing at the city of St. Louis, State of Missouri, have invented 5 ed a certain new and useful Improvement in Paper-Supports for Writing-Machines, of which the following is a full, clear, and exact description, such as will enable others skilled in the art to which it appertains to 10 make and use the same, reference being had to the accompanying drawings, forming part of this specification, in which—

Figure 1 is a front view of one form of typewriter paper carriage equipped with my 15 improved paper support. Fig. 2 is a vertical section on line 2—2 of Fig. 1. Fig. 3 is a bottom view of the mounting for one of the holding elements.

My invention relates broadly to writing 20 machines, and specifically to a form of paper holding mechanism for holding paper in proper position on the printing line while the pressure rolls are cast off.

The principal object of my invention is to 25 provide a simple and efficient form of mechanism for holding a sheet or sheets adapted to receive a plurality of entries in proper position on the printing line of a writing machine, while another sheet, which is adapted 30 to receive a fewer number of entries is being inserted in the machine or withdrawn therefrom.

In various forms of billing, it is desirable 35 to make a ledger or book entry at the same time that an invoice or statement is prepared. Obviously the ledger or book sheet is adapted to receive a number of entries, for which entries it may be desired to make 40 separate invoices or statements. The making of the entry on the book or ledger sheet is accomplished simultaneously with the 45 making of the invoice by the use of carbon or transfer paper, and an essential manipulation in such billing is the proper positioning of the invoice sheet upon the ledger sheet and both sheets relative to the printing line of the machine.

It is the universal practice in writing machines that the paper is held upon the platen 50 by pressure rolls which maintain it in proper alignment and insure its proper spacing. When the pressure rolls are thrown off, the paper is left free and may be removed from the platen.

55 By the use of the device herein described

and illustrated, it is possible to maintain a sheet in proper position relative to the printing line while the pressure rolls are thrown off and while another sheet, which for convenience will be called an invoice sheet, may 60 be removed and replaced with another.

These and other objects of my invention will be obvious upon an understanding of the device illustrated, wherein, as shown in Fig. 1, 1 represents the end frames of the 65 paper carriage, 2 the front bar connecting said end frames, and 4 a platen shaft journaled in said end frames. The platen 5 is carried upon the platen shaft 4 and may be rotated by manipulation of the thumb wheel 70 6. As shown in Fig. 2, a shaft 7 is carried in links 8; one of said links being pivoted on each of end frames 1. Said shaft 7 carries the pressure rolls 9 and leaf springs 10 tend to force shaft 7 toward the platen 5 and hold 75 the pressure rolls 9 in engagement therewith. One of the links 8 is formed with a lever arm 11 which may be swung downward by pressure on a key 12 so as to swing shaft 7 rearwardly to remove pressure rolls 9 from 80 platen 5. A locking device is provided in the form of a link 14 having a notched portion 15 adapted to engage on the pin 16 seated on one of the end frames. The notched portion 15 is impelled into engagement with the pin 16 by a spring 17 upon 85 suitable depression of key 12, which causes longitudinal movement of link 14.

Upon the front bar 2 are carried the 90 brackets 18 which are slidable longitudinally on said bar 2 and each of which forms a support for a paper guide 19, which embraces the platen and a rotatable sleeve 20 which carries a holding element 21. The sleeves 20 slide upon a rotatable shaft 22 95 which passes through a portion of the brackets 18. The rotatable shaft 22 is provided with a longitudinal slot 24 in which engage pins 25 carried on the sleeves 20. This pin and slot engagement of sleeves 20 on shaft 22 causes rotation of said sleeves when 100 said shaft is rotated. Rotation of shaft 22 is accomplished by means of a lever arm 26 and a link 27 which connects said lever arm with the key 12. Depression of key 105 12 moves link 27 downwardly and rotates shaft 22 clockwise, as shown in Fig. 2. Set screws 28 provide a means for securing brackets 18 in proper position on front bar 2.

The disposal of holding elements 21 is such that they will engage paper supported on the platen 5 when the shaft 22 is rotated in the manner just described, and 5 hold said paper in position relative to the printing line while the pressure rolls 9 are thrown off.

The preferred form of retaining member, as illustrated in Fig. 2, is provided with 10 a short needle point 29 which may engage several sheets of paper, so that in case several ledger or book sheets are to be written upon simultaneously, all will be held in proper position. This preferred form may 15 have a stop member 30 in the form of a small disk which engages the paper to prevent the needle point penetrating too far. To accommodate the needle point, I score a slight annular groove represented at 31 in 20 Fig. 2, around the platen in the line traversed by the needle point 29.

When a holding element is in position to engage the paper, its needle point will lie in this groove, and will not penetrate the 25 platen. As a consequence, either one or a plurality of sheets may be held in proper position without the platen being engaged by the points, the sheets so impaled upon the points being held both in proper position 30 relative to the printing line, and in proper position relative to one another so that proper alinement of the printing will be maintained on all of the sheets.

It is obvious that the holding elements 21 35 may operate at one side of guide fingers 19, or the guide fingers may be provided with apertures 19^a through which the holding elements may operate to engage the edges of the ledger sheet 32. As the ledger sheet 40 32 is universally wider than the invoice sheets 34, there will be a space at the sides of such invoice sheets for the operation of the holding elements 21. Suitable paper guides 35 are provided to support the invoice sheets 34.

In the operation of my improved device in billing, the ledger sheet 32 is inserted in the machine with an invoice sheet 34 there-over, a transfer sheet being interposed between the two. The item is then entered 50 simultaneously on the invoice and ledger sheets. When all items which are to appear on the invoice sheet have been entered, key 12 is depressed, thereby throwing holding 55 elements 21 into engagement with ledger sheet 32 and disengaging pressure rolls 9 from the paper. It is evident then that ledger sheet 32 will be securely held in position relative to the printing line, and that 60 invoice sheet 34 being released by pressure rolls 9, may be removed and replaced by another invoice sheet.

It will be understood that upon the depression of key 12, link 14 will engage pin 65 16 to lock said key in depressed position,

thereby holding pressure rolls 9 out of engagement with the paper, and holding elements 21 in engagement with the paper. The locking device may be thrown off by pressure on the key 35 which disengages 70 notch 15 from pin 16, permitting pressure rolls 9 to spring back into engagement with the paper under the influence of springs 10, which springs also, by the elevation of lever arm 11, reversely rotate shaft 22 and 75 disengage holding elements 21 from the paper. In this fashion, a plurality of invoices and ledger entries may be made simultaneously without removing the ledger sheet from the machine.

From the foregoing, it is obvious that my improved paper holding device is operated upon the manipulation of the mechanism for throwing off the pressure rolls, and it is further obvious that my improved holding device engages paper on the platen when the pressure rolls are thrown off, and does so without the necessity of any added manipulation of the paper. It is likewise obvious that this device does not require specially formed paper, such as paper with perforations therein, and that it will engage the paper, no matter how far the paper has been advanced upon the platen.

It is further obvious that this device permits the removal and insertion of sheets between the platen and the sheets which are held in writing position, and furthermore, that inasmuch as the held sheets are maintained in position by impalement on the 90 needle points, a proper relative position of said sheets will be maintained.

I am aware that modifications in the embodiment of my invention may be made, and I am also aware that other portions of the 100 device may be altered in obvious fashion without departing from the spirit or essence of the invention. Consequently, I do not intend that my invention be limited to the 105 specific form illustrated.

What I claim as my invention is:

1. A paper holding mechanism for writing machines including the combination of a revoluble platen, holding elements movable toward and from the platen, operating mechanism for moving said holding elements, and impaling members carried by said holding elements and adapted to penetrate paper supported on the platen to retain the paper in fixed position relative to the printing line, the platen being formed to accommodate the said impaling elements.

2. A paper support for writing machines including the combination of a platen arranged for line spacing movement, holding elements movable relative to the platen, means for manipulating said holding elements to engage and disengage paper supported on the platen, and impaling members carried by the holding elements and adapt-

ed to engage one or more sheets supported on the platen to hold the same in fixed position relative to the printing line.

3. In a device of the class described, the combination of a paper carriage, a platen, holding means for coöperating with the platen in line spacing movement, means for rendering said holding means inoperative, holding elements on the carriage and movable to transfix paper on the platen to retain it in position when the holding means is cast off, and means for moving said holding elements to engage and disengage paper supported on the platen.
- 10 4. In a device of the class described in combination with a movable platen for supporting paper, an impaling holding element movable to transfix paper on the platen to retain it in fixed position, the platen being formed to accommodate the impaling ele-

ment, and manipulative means for operating said holding element to engage and disengage paper supported on the platen.

5. In a device of the class described in combination with a movable platen for supporting paper, an impaling member adapted for movement toward the platen to transfix a plurality of sheets supported on the platen to hold them in fixed position, and means for moving said impaling member into and out of engagement with paper supported on the platen. 25 30

In testimony whereof I hereunto affix my signature in the presence of two witnesses, this 29th day of Nov., 1913.

OTTO THIEME.
